UNITED STATES PATENT OFFICE.

GUSTAVUS HAMEL, OF DE SOTO, MISSOURI.

COMBINED CHAIR AND LOUNGE.

SPECIFICATION forming part of Letters Patent No. 357,383, dated February 8, 1887.

Application filed May 27, 1886. Serial No. 203,429. (No model.)

To all whom it may concern:

Be it known that I, GUSTAVUS HAMEL, of De Soto, in the county of Jefferson and State of Missouri, have invented a new and Improved 5 Combined Chair and Lounge, of which the following is a full, clear, and exact description.

My invention relates to the construction of a combined chair and lounge wherein the parts are so arranged that the back of the chair may be adjusted to any angle desired, and wherein the attachment constituting the foot-rest or foot of the lounge may be disposed beneath the main seat of the chair when not use.

Reference is to be had to the accompanying 15 drawings, forming a part of this specification, in which similar figures of reference indicate corresponding parts in all the figures.

Figure 1 is a side view of my improved chair, representing the same as it appears when adjusted to use as a reclining-chair, certain portions being broken away. Fig. 2 is a sectional view taken on line *x x* of Fig. 1. Fig. 3 is a side view representing the parts as they appear when adjusted to constitute a lounge; 25 and Fig. 4 is a detail view illustrating the construction of the slotted socket, which serves as a support for the rear end of the main seat.

In constructing the chair forming the subject-matter of this application, I provide a 30 main frame, 10, which consists of side bars, 11, legs 14, arms 15, upper cross-bars, 12, lower cross-bars, 13, and longitudinal bracing-bars 16, the legs 14 and arms 15 of each side of the chair being made of one strip of wood bent to 35 a form to constitute the parts named.

The seat 17 is constructed upon a frame, 18, the forward end of which is formed with hooks that rest upon the forward main cross-bar, 12, while the rear end of the seat is supported by 40 studs 19, which ride in pivotally-mounted and slotted brackets 20, said brackets being secured to the side strips, 11, in the position best shown in Figs. 1 and 3.

The frame 21 of the back 22 is hinged or pivotally connected to the rear end of the frame 18, the studs 19 being employed for the purpose of establishing this connection. To the inner face of each of the arms 15 I connect a curved toothed rack, 23, and these racks act 45 as supports for the back of the chair, the frame 50

21 being provided with pins 2, that are engaged by the teeth of the racks 23.

From this construction it will be seen that the back and seat may be adjusted to meet the requirements of the occupant of the chair, this 55 adjustment being brought about by lifting the racks 23 from engagement with the pins 2 and bringing said pins into engagement with such teeth of the rack as will give the required inclination, the seat-frame 18 swinging upon its 60 connection with the front cross-bar, 12, and its studs or pins 19 riding in the slots of the brackets 20.

In connection with the back and seat of the chair, I employ a foot-rest, 25, upon one end of 65 which there are secured hooks 26, that are designed to engage when the foot-rest is in use with the forward cross-bar, 12, and if the combined chair and lounge were to be used as a reclining-chair the forward end of the foot-rest 70 would rest upon the floor, as shown in Fig. 1; but if the combined chair and lounge were to be used as a lounge the forward end of the foot-rest would be supported by folding legs 75 27, which legs in this case would be moved to the position in which they are shown in Fig. 3, but when the device is used as illustrated in Fig. 1 they would be folded up beneath the foot-rest 25.

When the foot-rest is not in use either as 80 the foot-rest to the lounge or as a foot-rest for the reclining chair, its hooks 26 are caught upon the rear cross-bar, 13, and its forward end is supported by the front cross-bar, 13, as indicated by dotted lines in Fig. 1.

Having thus fully described my invention, what I claim as new, and desire to secure by Letters Patent, is—

1. The combination, with the main supporting-frame, of a seat and back that are pivotally connected, the seat being provided with hooks that rest upon the upper front cross-bars of the frame and with pins which ride in slots of pivotally-mounted brackets carried by the frame, toothed racks being connected to 90 the arms of the frame and arranged to engage with pins carried by the back-frame, substantially as described.

2. The combination, with the frame 10, of a seat-frame, 18, formed with hooks that engage 95

with the forward upper cross-bar of the frame, slotted brackets 20, pins 19, carried by the seat-frame, a back-frame pivotally connected to the seat-frame and provided with pins 2, and 5 toothed racks pivotally connected to the arms of the frame 10, the seat and back frame being properly upholstered, substantially as described.

3. The combination, with the frame 10, of a seat-frame formed with hooks that engage with the forward and upper cross-bar of the frame, and pins 19, that ride in slots formed in piv-

otally-mounted brackets 20, a back-frame that is pivotally connected to the seat-frame, and provided with pins 2, that are engaged by 15 toothed racks 23, pivotally connected to the arms of the frame 10, a foot-rest, 25, formed with hooks 26, and legs 27, the foot-rest, seat, and back of the frame being properly upholstered.

GUST. HAMEL.
